United States Patent Office

Des. 203,617
Patented Feb. 1, 1966

203,617

CHARM OR SIMILAR ARTICLE

Henry Nunez, 1195 Jefferson Ave., Brooklyn, N.Y.

Filed June 16, 1964, Ser. No. 80,419

Term of patent 3½ years

(Cl. D45—17)

FIG.1

FIG.2

FIG. 1 is a front elevational view of a charm or similar article showing my new design;

FIG. 2 is an end elevation view thereof.

The essential features of the design reside in the full line portions on the drawing. The back of the design is plain and unornamented.

I claim:

The ornamental design for a charm or similar article, as shown and described.
